United States Patent Office

Des. 211,339
Patented June 11, 1968

211,339

INSECT CATCHER

Neil William Callahan, Jr., 18517 E. 7th St. N.,
Independence, Mo. 64050

Continuation-in-part of design application Ser. No. 7,433,
June 12, 1967. This application Nov. 24, 1967, Ser. No.
9,535

Term of patent 14 years

(Cl. D22—19)

FIGURE 1.

FIGURE 2.

FIGURE 3.

FIGURE 4.

FIGURE 1 is a top plan view of an insect catcher showing my new design;

FIGURE 2 is a front elevation thereof;

FIGURE 3 is a side elevation thereof; the opposite side is a mirror image of the side shown; and

FIGURE 4 is a rear elevation thereof.

This is a continuation-in-part of design application D. 7,433 filed June 12, 1967 and now abandoned.

I claim:

The ornamental design for an insect catcher, as shown.
